UNITED STATES PATENT OFFICE.

OLE O. STORLE, OF MILWAUKEE, WISCONSIN, ASSIGNOR OF ONE-HALF TO
JOHN H. GORDON, OF ROCHESTER, NEW YORK.

AUTOMATIC TRIP FOR GRAIN-BINDERS.

SPECIFICATION forming part of Letters Patent No. 380,605, dated April 3, 1888.

Application filed May 3, 1884. Serial No. 130,199. (No model.)

To all whom it may concern:

Be it known that I, OLE O. STORLE, of Milwaukee, in the county of Milwaukee and State of Wisconsin, have invented certain new and useful Improvements in Automatic Trips for Grain-Binders; and I do hereby declare that the following is a full, clear, and exact description thereof.

My invention relates to that class of grain-binding machines in which the binding mechanism is driven intermittently from a constantly-rotating wheel through the medium of a clutch which is tripped into action through intermediate devices by a compressor-arm which yields under the pressure of the gavel.

While the invention is applicable to machines of various forms, it is designed more particularly for machines of the so-called "Appleby type," and it is in this application that it is illustrated in the accompanying drawings.

As the grain delivering or packing mechanism and the mechanism for applying and fastening the band may be of ordinary construction and are foreign to my invention, it is deemed unnecessary to illustrate them in the drawings, which show only those parts immediately associated with my improvement.

Figure 1 represents an end elevation of a portion of a binder having my improvements embodied therein, with the parts in the normal position occupied during the formation of the gavel. Fig. 2 is a similar view with the binder-operating gear-wheel removed and the driving-clutch shown in section. Fig. 3 is an elevation of the clutch and trip mechanism in the position they occupy near the completion of the binding operation. Fig. 4 is a side elevation of the parts shown in Fig. 1. Fig. 5 is an end elevation of the machine in the act of discharging the bundle. Fig. 6 is a transverse section through the driving-clutch and the adjacent parts on the line $\alpha\alpha$ of Figs. 1, 3, and 5. Fig. 7 is a transverse section through the upper end of the compressor-operating pitman and the attendant parts. Fig. 8 is an elevation, partly in section, showing the driving and tripping devices in the positions occupied immediately after the tripping action.

Referring to the drawings, A represents the main binder-frame, of the usual Appleby type,

having an upright standard, a horizontal tubular top arm, A¹, supporting the knotter-driving shaft B, and a horizontal lower arm, A², containing the rock-shaft H, which carries the binding-needle, commonly known as the "needle-shaft."

The knotter-driving shaft B has fixed on one end, as usual, the large binder-operating gear-wheel C, containing a cam, e', to actuate the compressor. The needle-shaft H has at one end a rigid crank, H', connected by a pitman, I, to a wrist-pin, e, on the main gear-wheel, so that at each revolution of the wheel the needle is thrown upward and downward in the ordinary manner. The main gear receives an intermitting motion through a pinion, D, mounted loosely on a stud, E, projecting from an ear, E', on the binder-frame. The pinion D is provided, as in Fig. 6, with a tubular hub, D', which gives support to a constantly-revolving sprocket-wheel, F', mounted thereon, this wheel receiving motion through a chain, F². The driving-wheel F is formed on the side next to the pinion D with a peripheral rim or flange having internal teeth or shoulders, f.

To the pinion D at G' is pivoted an angular clutch-dog, G, having at its inner end a lateral roller or projection, g', projecting within the side of the driving-wheel F. A spring, g², seated within and carried by the pinion D, bears at one end against the clutch-dog and tends to force its inner end outward into engagement with the shoulders f of the driving-wheel. When the parts are thus engaged, motion is communicated from the wheel F through the dog G to pinion D and thence to the binder-gear. To hold this clutch-dog normally out of action and permit its engagement only when the gavel has acquired the proper size for binding, I make use of the parts which I will now describe.

To the end of the rock-shaft J which carries the trip and compressor J² is fixed a crank, J', connected by a pitman, K, to an arm, L, which latter is pivoted to the binder-frame at l and actuated through a stud or roller, l', on its side by a cam, e', of the binder-gear C, the general arrangement being similar to that in the existing machines.

The compressor-operating pitman K is pro-

vided near its upper end with a lateral stud or shoulder, K', to control the clutch-tripping device, hereinafter described. To the main binder-gear C, or to the end of its shaft, I secure in such manner as to revolve therewith the clutch-tripping arm Q, of T form, one end of which is widened, as shown at q, and arranged in such position that when the compressor is in its elevated position this end 10 will abut against and be arrested by the stud K' on the compressor-operating pitman. The opposite end, q', of the trip-arm is shaped and arranged in such position that when the arm is arrested by the stud K' the end q' will stand 15 in the path of the clutch-dog G, so that as the dog revolves with the pinion D it will encounter the end q' and be thrown thereby into the position shown in Fig. 2, so as to disengage the driving-wheel F and permit the pinion to 20 stop while the driver continues its motion. When the compressor-pitman is moved so as to carry its stud K' out of engagement with the trip Q, the latter will yield and permit the clutch-dog G to re-engage the driving-wheel 25 F and again set the binder in motion. In order to permit the movement of the pitman for this purpose and to give an elastic support to the compressor, I unite the upper end of the compressor-pitman K with the controlling- 30 lever L by a spring-connection such as shown more particularly in Fig. 7. The upper end of the pitman is reduced in size and fashioned into a tenon, k³, having a shoulder, k², at its lower end. On this tenon I mount the arms 35 of a C-shaped frame, M, the lower end of which bears upon the shoulder k². The controlling-lever L is attached at its outer end to a journal or pivot, m, on the frame M.

Within the frame M and upon its lower arm 40 I seat the compressor-spring N. On top of this spring around the tenon I mount a plate, o, having a tubular or cup-like neck, O, which extends upward loosely through the top of the frame M. In this plate I seat the trip-spring 45 P, the upper end of which bears beneath an adjustable nut, k⁴, screwed on the upper end of the pitman-tenon. This trip-spring is weaker than the compressor-spring. As the lever L under the influence of the cam urges 50 the frame M upward in the act of compressing the grain, the nut k⁴ encounters the end of the plate or housing O, so that the strength of the spring N is brought to bear in effecting the compression. Beneath the trip-spring P there 55 is inserted a series of removable washers, p, by which the tension of the trip-spring may be varied as desired. The advantage of adjusting the trip-spring by these washers instead of by the nut k⁴ lies in the fact that it 60 always affords sufficient space between the nut k⁴ and the top of the plate O to admit of the pitman K descending sufficiently to release the trip Q. If the nut k⁴ were turned down, it 65 might happen that the pitman would have an insufficient movement to release the trip.

In place of the washers other suitable de-

vices may be employed beneath the trip-spring p to regulate its tension.

The action of the parts is as follows: The compressor, its actuating-arm L, and the spring-connection stand normally as shown in Figs. 1, 2, and 7, the stud K' being in contact with the trip Q, which keeps the driving-clutch out of action. When the gavel acquires the pre-determined size, its pressure against the arm J² causes the pitman K to be drawn downward, 70 overcoming the resistance of the trip-spring P. As the pitman descends its stud K' is carried below the end q of the trip Q, which, being released, yields and swings over the stud, 80 as in Fig. 8. This permits the spring g² to throw the outer end of the clutch-dog G past the end of the trip, so that the clutch is immediately brought into action and the binder set in motion. The outer end of the clutch-dog 85 G is widened, as shown at g, so that although the dog is carried with the pinion in its rotation it remains in contact with the trip, as in Fig. 8, and holds the latter out of action until the pitman has been lowered by the lever L, 90 so that there is no danger of the stud K re-engaging the trip. The parts now continue their movement, assuming successively the position 95 shown in Fig. 5, so that the compressor is depressed to discharge the bundle, the position shown in Fig. 3, in which the trip Q, having nearly completed its revolution, is again in the path of the trip G, and finally the original position shown in Figs. 1 and 2, in which the dog has encountered and been thrown out 100 of action by the trip Q, which has in its turn been arrested by the stud K'.

In order to render the action of the parts easy and certain, the trip-arm Q may be fitted loosely to the carrying wheel or shaft, as indicated by dotted lines a⁴ in Fig. 8, in such manner as to have a slight freedom of movement thereon in the direction of its rotation, so that it will readily yield and move forward under the pressure of the dog G when released by the stud K'. 105

When the parts are constructed as shown in the drawings, this independent motion of the arm Q is not necessary, as the pressure of the grain exerted through the needle-arm and the compressor and the intermediate connections to the wheel C will tend to turn the wheel 115 slightly forward, so that the arm Q may advance from under the dog G as soon as the stud K' moves away from its opposite end. 120

Having thus described my invention, what I claim is—

1. In a grain-binder, the rotary clutch-tripping arm driven by the knotter-driving shaft, in combination with a lug or stop on the compressor-operating pitman, and a clutch-dog 125 pivoted to the pinion, which actuates the binder-operating gear-wheel, substantially as set forth.

2. In a grain-binder, a rotary clutch-tripping arm driven by the knotter-driving shaft, in combination with a compressor-operating pit- 130

man having a lug or stop for engagement with said trip, and a tripping-spring secured to said pitman.

3. In a grain-binder, the combination of a binder-operating gear-wheel pinion and clutch, with a clutch-dog attached to the said pinion, a rotary clutch-tripping arm adapted to revolve with the binder-operating gear-wheel, a compressor-operating pitman, a trip spring connected thereto, a lug or stop on the pitman for engagement with said clutch-trip, and driving-connections between the binder-operating wheel and the pitman.

4. In a grain-binder, the combination of a binder-operating gear-wheel, pinion, and clutch with a clutch-dog pivoted to said pinion, a clutch-tripping arm adapted to revolve with the binder-operating gear, the compressor-operating pitman with a stud to arrest the trip-arm, driving-connections between the binder-operating wheel and the pitman, the frame mounted on said pitman and containing a compressor-spring, a plate or housing thereon, and a trip-spring seated on said plate and bearing against a nut or collar on the pitman.

5. In a grain-binder, the combination of a binder-operating gear-wheel, clutch-pinion, sprocket-wheel and clutch-dog pivoted to said pinion with a rotary clutch-tripping arm adapted to revolve with the binder-operating gear-wheel, a compressor-operating pitman having a trip-spring secured to the upper part, and a lug or stop on said pitman for engagement with the rotary trip-arm.

6. In a grain-binder, the combination, with 35 a binder driving-gear and cam-wheel, the clutch-pinion engaging said wheel, the constantly-rotating driving-wheel F, the clutch-dog pivoted to the pinion, the rotary trip adapted to revolve with the binder driving-gear, the compressor-operating pitman provided with a stud to engage the trip, a lever, L, actuated by the cam of the binder driving-gear, a frame, M, attached to said lever and movably mounted on the pitman, the compressor-spring N, and the relatively-weak trip-spring acting to urge the pitman upward, as 40 45 described and shown.

7. In a grain-binder, the combination of the compressor-operating pitman having at its upper end the tenon with the shoulder k² and screw-thread, the frame M, seated on said shoulder and connected with an operating-lever, L, the compressor-spring N, sustained by said frame, the independently-movable plate 50 55 O, sustained upon the compressor-spring, the relatively-weak trip-spring mounted on said plate, a series of washers, p, seated beneath the trip-spring, and the nut k⁴, applied to the pitman and seated on top of the trip-spring. 60

In testimony that I claim the foregoing I have hereunto set my hand, at Milwaukee, in the county of Milwaukee and State of Wisconsin, in the presence of two witnesses.

OLE O. STORLE.
